(74) *Attorney, Agent, or Firm* — Hanrahan Law Firm, P.A.; Benjamin M. Hanrahan

(57) **CLAIM**

The ornamental design for a milk frother stand, as shown and described.

DESCRIPTION

FIG. 1 is a top perspective view of a milk frother stand showing our new design.

FIG. 2 is a bottom perspective view thereof.

FIG. 3 is a front view thereof.

FIG. 4 is a right side view thereof.

FIG. 5 is a rear view thereof.

FIG. 6 is a left side view thereof.

FIG. 7 is a top view thereof.

FIG. 8 is a bottom view thereof; and,

FIG. 9 is another top perspective view thereof with a milk frother shown in broken lines.

The broken lines in FIG. 9 are for the purpose of illustrating environment and form no part of the claimed design.

1 Claim, 9 Drawing Sheets
